CLAIM

The ornamental design for spray dispenser, as shown and described.

DESCRIPTION

FIG. 1 is a right side view of spray dispenser, showing the new design, where the right side view is a mirror image of the left side view;

FIG. 2 is a front view thereof;

FIG. 3 is a top view thereof;

FIG. 4 is a rear view thereof; and,

FIG. 5 is a bottom view thereof, where broken lines in the drawings indicate the boundary of the claimed design and form no part of the claimed design.
